UNITED STATES PATENT OFFICE.

LEON WOLF, OF NEW YORK, AND ISIDOR RYBACK, OF BROOKLYN, NEW YORK; SAID WOLF ASSIGNOR TO WILLIAM WOLF.

APPARATUS FOR INSERTING HAT-LININGS.

1,299,089.

Specification of Letters Patent.

Patented Apr. 1, 1919.

Application filed December 6, 1917. Serial No. 205,820.

To all whom it may concern:

Be it known that we, LEON WOLF, of the borough of Manhattan, city, county, and State of New York, a subject of the Emperor 5 of Austria, and ISIDOR RYBACK, of the borough of Brooklyn, city, county, and State of New York, a citizen of the United States of America, have invented certain new and useful Improvements in Apparatus for Inserting Hat-Linings, of which the following 10 is a specification.

The object of our invention is the improvement in the apparatus for fastening hat linings. It has hitherto been the custom 15 to sew the bottom portion of the lining to the hat by hand or by machine. This is always a slow process and requires a skilled and careful operator. Our apparatus enables the lining to be inserted and retained without 20 the employment of any skilled or careful sewing and if desired without any sewing at all.

Figure 1 is a perspective view of one form 25 of the apparatus capable of being used in connection with our invention with parts broken away for the sake of clearness.

Fig. 1^a is a horizontal sectional view on line a—a of Fig. 1^b of a modification of the 30 supporting means.

Fig. 1^b is a vertical sectional view of this element.

Fig. 1^c is a perspective view of the modified form of heating element guard.

Fig. 2 is a vertical sectional view of the 35 supporting member for the hat with parts broken away showing the hat and lining in position.

Fig. 3 is a detailed view showing the ends of the expandable support of Fig. 1.

Fig. 4 is a vertical sectional view of a 40 modified form of the invention taken on line 4, 4 of Fig. 5.

Fig. 5 is a horizontal sectional view on a line 5, 5 of Fig. 4 with parts broken away.

Our apparatus contemplates the use of a lining in combination with an adhesive strip. This may be of rubberized buckram or any other adhesive material.

Considering first the form of the invention 50 disclosed in Fig. 1, 1 indicates a supporting member provided with means for contracting and expanding same. In the present instance, this property is obtained by forming the ring-like supporting member of resilient material. The supporting member 1 is 55 loosely carried on the standard 2 from which

extends arms 3 in a radial direction through the slots 4 of the expandable member. It will be apparent that when the handles 5 are moved toward each other the supporting member will be contracted to admit of placing thereon a hat in the manner indicated in Fig. 2. After the hat is in position the handles 5 are released and the member 1 allowed to expand freely. It will be observed in the present instance that the arms 3 are integral with the central standard 2 and that the slots 4 are in the supporting member 1. In Figs. 1^a and 1^b the reverse arrangement is shown. The radial arms 3' are rigidly connected to the supporting member 1 and extend through the slots 4' in the head 10 of the central standard 2'. The supporting member 1 in addition to being of resilient material is also of heat conducting 75 material for the purpose of subjecting the lining and hat to heat as well as pressure. One method of utilizing the heating element is shown in Fig. 1 where the electric resist- 80 ing element 6 is placed inside the ring 1 and covered by means of heat non-conducting material such as asbestos, here shown as the covering 7 between which and the outward ring 1 the resistance element is placed. The conductor 8 for supplying current to the re- 85 sistance element is conveniently carried by the central standard 2 and thence by way of the radial arms to the resistance element 6. In the modification shown in Fig. 1^b the conductors 8 emerge through the opening 9 in the standard 2' and pass beneath the head 10 of the central standard to the resistance element. The hat is placed in position on the supporting member 1 while the latter 90 is contracted and, upon the handles 5 being released, the inherent resiliency of the material will exercise pressure on the lining 11, with its turned in strip 12, the adhesive band 13 and the head-size 31, heat being applied 95 through the heating element sufficient to cause adhesion between the adhesive band, 100 the hat and the lining. In the preferred method of operation, the adhesive band is attached to the lining by sewing or otherwise previous to the mounting of the hat on the device, the adhesive band and the lining being 105 so arranged with reference to each other and the head-size that the adhesive band intervenes between the hat and the lining. If desired, however, the band of adhesive ma- 110 terial may be unattached and may be interposed freely between the lining and the hat

when the parts are subjected to heat and pressure as before. In Fig. 1^c is shown a modification of Fig. 1 in that instead of having a covering of heat non-conducting material, the expansible ring member 1^c is provided with integral prongs 2^c which are bent back upon the supporting member to form a channel 3^c in which the heating element may be disposed.

- 10 In the modifications shown in Figs. 4 and 5 the supporting member 14 is here shown in the form of a plurality of segments 15 expansible and contractible in some suitable manner here taking the following form: Mounted on each segment 15 is a pin 16 which extends down through radial slots 17 in the carrying member 18 and at their lower ends these pins are provided with rollers 19 which extend into the cam slots 20 of the rotatable member 21. This latter member is keyed to shaft 22 provided at its lower end and with the gear 23 which meshes with a rack 24 slidably mounted in the bearings 25 and normally rigid in the position shown in Fig. 4 by means of the spring 26 anchored at one end on one of the bearings 25 and secured on its other end to adjustable member 27. 28 is a bearing member for actuating the sliding rack 24. 29 indicates projections on the adjustable segments 15 which dove-tail or telescope to provide the continuous surface between the adjustable segments when they are in expanded position.
- 35 The heating element in the form shown in Figs. 4 and 5 here consists of a gas burner 30 preferably of the general shape as outlined in the member 14. The carrying member 18 in this instance 40 also serves the function of a frame guard to prevent the direct application of heat to the hat, the heat being as previously transferred by conduction through the expansible members. The method outlined in connection 45 with the modifications shown in Figs. 4 and 5 is the same as that used in connection with Figs. 1 and 2, and similar lettering is used to denote the hat, the lining and the piece of adhesive material.
- 50 Our method and apparatus, therefore, is not only adapted to women's hats but can be used on men's hats and employed as a means of causing the sweat-band to adhere to the crown of a hat or for blocking purposes.
- 55 Another important feature is that it enables the lining to be easily removed. All that is needed is to apply heat to the brim of the crown of the hat in the manner indicated, causing the adhesive material to melt and 60 the lining can then be removed. It can then be put back into the hat as before or used again in another hat. One standard lining can be used for any head size.

Having described our invention what we claim is:—

65

1. A device of the character described comprising: an expansible member adapted to support a hat and a lining therefor, means for contraction of said member, and means for applying heat to the hat by conduction 70 through the expansible member.

2. A device of the character described comprising: an expansible member adapted to support a hat and a lining therefor, means for contraction of said member, a heating 75 element associated with said expansible member, and means for preventing said element from acting directly on the hat.

3. A device of the character described comprising: a ring-like member adapted to support a hat and a lining therefor, the ring member being of resilient material with overlapping ends and having a heating element for supplying heat to the ring member, for the application of heat and pressure to 85 the lining.

80

4. A device of the character described consisting of an outer ring-like member of resilient heat conducting material the ends of which overlap, an inner non-conducting 90 ring, and a heating element arranged between the members.

5. In a device of the character described, a ring-like member of resilient and heat conducting material adapted to support a hat 95 and a lining therefor, the ring member having overlapping ends, and an electric heating element adapted to expand and contract with said ring, for the application of heat and pressure to the lining.

100

6. A device of the character described comprising: a holder member centrally disposed having radial spokes supporting an expansible ring-like member adapted to support a hat, the ring member having overlapping 105 ends and the spokes having a sliding connection with one of said members to permit the expansion and contraction of the ring member.

7. In a device of the character described, 110 a central standard member having radial arms, an expansible ring member with overlapping fingers, and a heat conducting element, the ring member having means for contraction and expansion thereof and the 115 heat conducting element extending through the central standard and along one of the radial arms of the standard to the ring member for the application of heat and pressure to the hat lining.
